UNITED STATES PATENT OFFICE

HARRY A. SUMMERS, OF BROOKLYN, NEW YORK, AND SIGURD A. SOLLIE, OF PALO ALTO, CALIFORNIA, ASSIGNORS TO FEDERAL TELEGRAPH COMPANY, OF SAN FRANCISCO, CALIFORNIA, A CORPORATION OF CALIFORNIA

PHONOGRAPH PICK-UP APPARATUS

Application filed November 5, 1927, Serial No. 231,374. Renewed May 8, 1930.

Our invention relates broadly to electrical phonographs and more particularly to an electrical pickup device adapted to reproduce sound from phonograph records.

5 One of the objects of our invention is to provide a construction of electrical pick-up apparatus for electrical phonographs which is capable of manufacture and production inexpensively on a quantity production basis.

10 Another object of our invention is to provide a construction of electrical phonograph pick-up which is designed to reproduce accurately the entire range of musical notes encountered in phonograph reproduction.

15 A further object of our invention resides in the construction of the pole pieces in an electrical phonograph pick-up device and mounting for an armature member in an electrical phonograph pick-up where the armature member is free to rock without the provision of mechanical pivots or trunnions at the ends thereof.

20 Other and further objects of our invention reside in the construction of an armature member for an electrical phonograph pick-up, wherein the armature member is provided with a central longitudinally extending body portion, a wedge or triangularly shaped head thereon and laterally protruding portions at 25 opposite sides of the central body portion, the laterally protruding portions being provided with knife edges arranged to pivot upon a bearing provided in the pole face of one of the pole pieces constituting the electrical phonograph pick-up.

25 Still further objects of our invention reside in the method of mounting the armature member in an electrical phonograph pick-up as set forth in the following specification, 30 by reference to the accompanying drawings, in which:

35 Figure 1 is a perspective view showing the completed electrical phonograph pick-up of our invention; Fig. 2 is a plan view of the phonograph pick-up of our invention; Fig. 3 is an end view of the phonograph pick-up of our invention illustrated partially in cross-section to show the arrangement of pole pieces and the mounting of the armature with respect thereto; Fig. 4 is a side view of the cover

member which we provide on the phonograph pick-up of our invention; Fig. 5 is a side elevation of the phonograph pick-up with the cover removed therefrom; Fig. 6 is a longitudinal cross-sectional view taken through the phonograph pick-up of our invention; and Fig. 7 is a view of the several parts constituting the electrical phonograph pick-up and illustrating the relationship of the parts preparatory to the assembly process for the electrical phonograph pick-up device.

40 Referring to the drawings in more detail, reference character 1 designates a foundation plate structure which carries the several parts of the electrical phonograph pick-up. Upstanding lugs 2 and 3 are provided on base 1, forming trunnions for the pivotal mounting of yoke member 6 in bearings 4 and 5. The yoke 6 is secured to the end of swivel arm 7 which is pivotally mounted upon the phonograph cabinet structure. A casing 8 is provided which fits snugly around a flanged portion of the base 1 and encloses the several 45 parts of the electrical phonograph pick-up. A permanent magnet 9 is mounted on the foundation plate 1 and is retained in position by means of a strip member 10 having a screw device 11 passing therethrough and anchored in a screw threaded bushing 12 which is cast into the upstanding portion 14 of the base 1. The base 1 is provided with an inclined plane portion 15 extending between the poles of the permanent magnet 9. The base member 1 is 50 apertured as represented at 16 enabling armature 17 to protrude therethrough. The armature 17 has an inwardly extending bore 19 with a stylus 18 secured therein for engagement with a sound record shown at 36 in Fig. 1 as carried by a record table 37. A pair of 55 pole pieces 20 and 21 shaped as shown in Fig. 7 are mounted between the ends of the permanent magnet 9 and have sets of pole faces directed toward each other. The pole faces are bifurcated at 20^a—20^b and at 21^a—21^b. The pole faces 20^a are V shaped and have a 60 non-magnetic metal central portion 20^b set therein providing a bearing surface. Pole faces 21^a are substantially semi-circular in contour as clearly shown in Fig. 7. The pole faces 20^c and 21^c are cut at an acute angle

65 60 65 70 75 80 85 90 95 100

directed toward each other in an upward direction. The armature member 17 includes a central body portion and a wedge shaped head 22 which fits between the pole faces 20^c and 21^c with a rubber strip member 24 wrapped over the wedge shaped head 22 and fitting between the pole faces 20^c and 21^c and the adjustable stops 25 and 26. These stops are substantially flat with inwardly extending tongues 25^a and 26^a, the tongues being bent at acute angles with respect to the under surface of the plate members and providing abutments adjacent the bifurcated pole faces in slots 20^d and 21^d with the resilient strip 24 which extends over the wedge shaped head 22.

The resilient strip 24 serves as a cushion between the sides of the wedge shaped head 22 and the tongues 25^a and 26^a. Each of the plates 25 and 26 are slotted as represented at 25^b and 26^b enabling screw members 25^c and 26^c to be screwed into pole pieces 20 and 21 and adjusted with respect to the wedge shaped head 22 of the armature 17. Sets of washers 25^d and 26^d are positioned with the heads of screws 25^c and 26^c and the plate members 25 and 26. The electromagnetic winding is shown in the form of a bobbin 28 wound upon the insulated support 27 which fits between the pole members 20 and 21 as illustrated with the sets of pole faces at opposite ends of the electromagnetic winding. The armature member 17 passes through the electromagnetic winding 28 and has the wedge shaped head 22 thereof engaged on opposite sides by the resilient strip 24. The laterally protruding portions of the armature are provided with knife edge faces 17^a and 17^b which engage the bearing member 20 in the V-shaped faces 20^a of the pole member 20. The opposite faces of the laterally protruding portions of the armature are circular as indicated at 17^c and 17^d conforming with the shape of the pole faces 21^a. A resilient strip 23 is seated between the rounded faces 17^e and 17^d which are spaced from the rounded faces 21^a of pole piece 21 by means of resilient strip 23. Rocking movement is imparted to the armature by the stylus 18 and torsional stresses occur in the resilient strip 23 as the rounded faces 17^e and 17^d tend to move the entire mass of the resilient strip 23 by shearing forces which are resisted by the inherent structure of the resilient strip 23. A screw device 29 extends into the end of the armature member and secures the stylus 18 in the recess 19 in the armature 17. Electrical conductors 32 extend from the electromagnetic winding 28 to the lug members 33^a and 33^b of binding posts 33 which are carried by terminal block 31 on the foundation plate structure 1. Flexible leads 30 extend from the binding posts 33 on the terminal block 31 through the hollow arm 7 to the input circuit of the amplification system constituting the

control means to the sound reproducer in the electrical phonograph apparatus.

The phonograph pick-up of our invention has proven highly efficient in operation and practical in its construction, and while we have described a preferred embodiment of the invention, we desire that it be understood that modifications may be made and that no limitations upon our invention are intended other than are imposed by the scope of the appended claims.

What we claim as new and desire to secure by Letters Patent of the United States is as follows:

1. An electrical phonograph pick-up comprising a foundation plate arranged to lie in a plane substantially parallel to a phonograph record during the movement of the pick-up over the record, an inclined plane member at one end of said plate, a pair of pole members mounted on said inclined plane member and directed toward each other laterally with respect to said plate, an armature mounted for swinging movement between said pole members in a plane passing through the longitudinal axis of said plate, and means at the opposite end of said plate member for pivotally supporting said phonograph pick-up.

2. An electrical phonograph pick-up comprising a foundation plate, an inclined plane member at one end of said plate, a permanent magnet carried by said plate member and extending on opposite sides of said inclined plane member, an electromagnetic winding, a pair of pole pieces mounted on said inclined plane and directed toward each other, said pole pieces having faces extending on opposite sides of said electromagnetic winding, one of said pole faces being arcuate in shape and the opposite pole face being V shaped, and an armature member having a rounded face at one side and knife edge contact faces at the opposite side with the knife edge of said armature member in engagement with said V shaped pole face, and resilient means between the rounded face of said armature member and the arcuate shaped pole face.

3. An electrical pick-up comprising a foundation plate member arranged to lie in a plane substantially parallel to a phonograph record during the movement of the pick-up over the record, an inclined plane at one end of said foundation plate member, a permanent magnet carried by said plate member and extending on opposite sides of said inclined plane, pole pieces carried by said inclined plane and directed toward each other, one of said pole pieces having a V shaped face, an armature member, a non-magnetic insert within said V shaped face providing a bearing for said armature member and means at the opposite end of said plate member for pivotally supporting said phonograph pick-up.

4. An electrical phonograph pick-up comprising a foundation plate member arranged to lie in a plane substantially parallel to a phonograph record during the movement of the pick-up over the record, a terminal block at one end of the plate member, an inclined platform at the opposite end of the plate member, a permanent magnet carried by said plate member and surrounding said platform, a pair of pole pieces fitted on said inclined platform and extending between the poles of said permanent magnet, an electromagnetic winding disposed between said pole pieces, an armature member rockable within said electromagnetic winding and driven by a stylus connected with said armature member and means on said plate member on opposite sides of said terminal block for pivotally supporting said phonograph pick-up. 5. In an electrical phonograph pick-up, an armature having a vertical central portion, a triangularly shaped head thereon, adjustable members on opposite sides of said triangularly shaped head for damping the movement of said armature, laterally extending portions on said armature, rounded faces at one side of said laterally extending portions and knife edges at opposite sides of said laterally extending portions. 6. In an electrical phonograph pick-up, a foundation plate member arranged to lie in a plane substantially parallel to a phonograph record during the movement of the pick-up over the record, an electromagnetic actuator carried by said foundation plate member, an electromagnetic winding, an armature pivotally mounted within said electromagnetic winding, pole members surrounding said electromagnetic winding, the pole members being bifurcated at their upper ends and aligned with respect to each other, adjustable plate members having tongues disposed at an angle to the plane of said plate members, a triangularly shaped head on said armature, a resilient member disposed between the sides of the triangularly shaped head and the tongues on said plate members and means adjacent one end of said plate member for pivotally supporting said phonograph pick-up. 7. In an electrical phonograph pick-up, a foundation plate member, an electromagnetic winding carried by said plate member, an armature member positioned within said winding, a pair of pole members having bifurcated pole tips directed toward each other, the upper set of pole tips being cut at an angle with respect thereto for resiliently damping the movement of said armature member and the lower set of pole tips having a pair of concave faces with the opposite pole tip having a pair of V shaped faces, said armature member having a pair of knife edges cooperating with the V shaped faces on one of the pole tips, and a rounded surface on said armature member cooperating with said concave faces, and resilient means between said concave faces and the rounded surface on said armature. 8. An electrical phonograph pick-up comprising a plate member arranged to lie in a plane substantially parallel to a phonograph record during the movement of the pick-up over the record, means located centrally of said plate member for retaining a permanent magnet in horizontal alignment thereon, an inclined plane adjacent one end of said plate member and between the poles of said permanent magnet, pole pieces secured to said inclined plane and directed toward each other between the poles of said permanent magnet, an electromagnetic winding, an armature member rockably mounted in said pole pieces and passing through said plate member substantially perpendicular to said inclined plane, a stylus carried by said armature member for imparting movement to said armature member from a sound record for effecting variable displacement of said armature with respect to said electromagnetic winding and means adjacent the opposite ends of said plate member for pivotally supporting said phonograph pick-up. 9. An electromagnetic translating device comprising, a base member, a permanent magnet carried by said base member, a pair of pole pieces between the poles of said permanent magnet, an inclined member on said base member adjacent one end thereof, means for mounting said pole pieces on said inclined member, an armature movable between said pole pieces, and a stylus carried by said armature, said armature being mounted so that said stylus is substantially perpendicular to said inclined member, whereby when said base member is in parallel relation to a phonograph record said stylus is disposed at an angle to said phonograph record. 10. An electromagnetic translating device as defined in claim 9 and means for rotatably mounting said base member at the end thereof opposite said inclined member. In testimony whereof we affix our signatures.
